R. D. ANDERSON.
GATE.
FILED OCT. 18, 1920.

UNITED STATES PATENT OFFICE.

ROBERT D. ANDERSON, OF ENID, OKLAHOMA.

GATE.

Application filed October 18, 1920. Serial No. 417,706.

To all whom it may concern:

Be it known that I, ROBERT D. ANDERSON, citizen of the United States, residing at Enid, in the county of Garfield and State of Oklahoma, have invented certain new and useful Improvements in Gates, of which the following is a specification.

This invention relates to new and useful improvements in gates which may swing and slide, the primary object of the invention being to provide a gate which may be moved so that its central portion is arranged adjacent the pivotal connection of the gate to prevent sagging of the same.

Another object of the invention is to provide a device of this nature including a supporting structure for the gate including a slotted upright through which the gate is slidable, said supporting structure also including means for retaining the gate in proper engaging position with rollers carried by the supporting structure.

Other objects and advantages of the invention will become apparent during the course of the following description.

In the accompanying drawings forming a part of the application and wherein like numerals are employed to designate like parts throughout the several views

Figure 1 is a side elevation of the invention illustrating the same in partly open position.

Figure 2 is a transverse section of the same taken on the line 2—2 of Figure 1, and

Figure 3 is a fragmentary transverse section of the same taken on the line 3—3 of Figure 1.

Referring now to the drawings wherein for the purpose of illustration is shown the preferred embodiment of the invention, the numeral 4 designates a fence post from which extend laterally projecting hinge hooks 5 adapted for engagement with loops 6 projecting from the rear face of an upright 7 constituting a part of the supporting structure for the gate indicated in its entirety by the numeral 8 and comprising a plurality of horizontal spaced beams 9, end uprights 10 and an intermediate upright 11 for retaining the horizontal bars in spaced parallel relation.

The upright 7 of the supporting structure is provided with as many transverse openings 12 as there are horizontal bars 9 in the gate so that these bars may be silda-

bly mounted through the openings. One of the intermediate slots is provided with a vertically disposed roller 13 mounted upon a pin or bolt 14 extending transversely of the opening, the roller being adapted for engagement with the lower longitudinal edge of the upper intermediate bar 9 of the gate.

In order to support the outer end of the gate, braces 15 arranged upon opposite sides of the gate are secured to the lower end of the upright 7 and extend upwardly at an angle thereto so that their free ends are disposed between the two intermediate horizontal bars 9 of the gate and arranged upon opposite sides thereof. The axle 16 of a second roller 17 is journaled in alignment with said first mentioned roller and transversely of the free ends of the braces 15 so that the roller engages the lower edge of the horizontal bar of the gate which is engaged with the roller 13. A pair of guide blocks 18 are secured to the inner faces of the free ends of the braces 15 to extend vertically and to be arranged upon opposite sides of the two intermediate horizontal bars of the gate and engaged with said bars so that these bars cannot become disengaged from the roller 17. It will also be apparent that by arranging these guide blocks 18 to engage opposite sides of the intermediate bars of the gate that the latter will be materially braced and prevented from wobbling.

A pair of brace rods 19 are provided to support the braces 15, and are arranged upon opposite sides of the gate so that their lower ends which are equipped with eyes 20 may be secured to the axle 16 and their upper ends extended through the upper end of the upright 7. Nuts 21 are threaded upon the upper ends of the brace rods 19 so that should the gate ever sag, the nuts may be tightened to overcome the difficulty.

From the foregoing description it will be obvious that the gate may be swung by the upright 7 pivoting upon the hinge members 5 and 6, or the gate may be slid upon the rollers 17 and 13. When the gate has been swung to an open position it is moved upon the rollers so that its intermediate portion is arranged adjacent the upright 7 so that sagging of the gate is prevented.

The foregoing description and the accompanying drawings have reference to the preferred or approved embodiment of my

invention. It is to be understood however that such changes may be made in construction and arrangement of parts, materials, dimensions, etc. may be made as may 5 prove expedient and fall within the scope of the appended claim.

Having thus fully described my invention what I claim as new and desire to secure by Letters Patent is:—

- 10 A supporting structure for sliding gates comprising an upright through which a gate is adapted to move, a roller carried thereby for engagement with the gate, a pair of laterally spaced parallel braces extending 15 upwardly at an angle from the lower end of said upright, an axle extending through the upper ends of said braces, a roller

mounted on said axle between said braces for engagement with the gate, a pair of spaced parallel brace rods having bearings 20 at their lower ends for said axle and arranged upon opposite sides of the gate, the upper ends of said rods being threaded and extended through the upper end of said upright, and nuts on said ends of the rods for 25 adjusting the same to effect the adjustment of the braces.

In testimony whereof I affix my signature in presence of two witnesses.

ROBERT D. ANDERSON.
